to Hollymade Hardware Manufacturing Com-
pany, Los Angeles, Calif., a corporation of Cali-
fornia

Application October 1, 1948, Serial No. 148,919

Term of patent 14 years

(Cl. D50—4)

To all whom it may concern:

Be it known that I, Robert C. Cerf, Jr., a citizen of the United States, residing in Los Angeles, in the county of Los Angeles and State of California, has invented a new, original, and ornamental Design for a Key Blank, of which the following is a specification, reference being had to the accompanying drawing forming a part thereof, in which:

Figure 1 is a front view of a key blank, showing my new design; and

Figure 2 is a cross-sectional view taken on the line 2—2 of Figure 1.

The dominant features of my design reside in the portions shown in full lines.

I claim:

The ornamental design for a key blank, as shown and described.

ROBERT C. CERF, JR.
